INTERNAL COMBUSTION ENGINE

Buford J. Schramm, 14805 S. Interstate 10, Tempe, Ariz. 85281, and Robert G. Everts, 2118 E. Burchwood Ave., Mesa, Ariz. 85204

Filed Oct. 23, 1974, Ser. No. 517,293

Term of patent 14 years

Int. Cl. D15—01

U.S. Cl. D77—1 R

FIG. 1

FIG. 2

FIG. 3

FIG. 4

FIG. 5

FIG. 6

FIG. 1 is a side elevational view of an internal combustion engine showing our new design;

FIG. 2 is a right end elevational view thereof;

FIG. 3 is a top plan view thereof;

FIG. 4 is a left end elevational view thereof;

FIG. 5 is a side elevational view thereof opposite to that shown in FIG. 1; and

FIG. 6 is a bottom plan view thereof.

We claim:

The ornamental design for an internal combustion engine, as shown.
